UNITED STATES PATENT OFFICE.

HENRY E. PARSON, OF BROOKLYN, NEW YORK.

BLAST-PIPE FOR STEEL-FURNACES.

SPECIFICATION forming part of Letters Patent No. 592,204, dated October 19, 1897.

Application filed March 24, 1897. Serial No. 628,948. (No model.)

To all whom it may concern:

Be it known that I, HENRY E. PARSON, a citizen of the United States, residing at Brooklyn, county of Kings, and State of New York, have invented certain new and useful Improvements in Blast-Pipes for Steel-Furnaces, of which the following is a specification.

This invention has reference to certain improvements in the blast-pipes for steel, reverberatory, and other furnaces by which the blast-supply of a fan-blower can be augmented by the blast produced by a steam-blower arranged in the blast-pipe, said steam-blower being located in proximity to an opening in the blast-pipe, closed by a suitable door, so that the steam-blower may be used in conjunction with the fan-blower, or used without the fan-blower on opening the door, as required by the furnace; and the invention consists of a blast-pipe for steel and other furnaces, and in which pipe is arranged a steam-blower having a number of nozzles, a steam-supply pipe for said blower, said blower being located in front of an opening in the blast-pipe, and a door for closing said opening, so that a fan-blower can be used in connection with the steam-blower, or the latter alone.

In the accompanying drawings, Figure 1 represents a vertical longitudinal section of a blast-pipe for furnaces, showing the position of the steam-blower with respect to the air-supply opening in the blast-pipe. Fig. 2 is a vertical transverse section on line 2 2, Fig. 1; and Fig. 3 is a sectional side elevation showing my blast-pipe in connection with a blower and furnace.

Similar letters of reference indicate corresponding parts.

Referring to the drawings, A represents the blast-pipe of a steel or other furnace F, which blast-pipe is connected as usual at one end with a fan-blower G, by which the blast is supplied to the furnace. It is necessary in steel-furnaces that the melting mass should be subjected to a blast greater in intensity than that supplied by a fan-blower, and for this purpose a steam-blower B is arranged in the blast-pipe and connected with a steam-

supply pipe B', said steam-blower being constructed with radial supply-pipes and a number of steam-jet nozzles b, and being of that type for which Letters Patent were granted to me heretofore, No. 582,483, dated May 11, 1897.

Adjacent to the steam-blower B, but back of the same, is arranged, in the upper part of the blast-pipe A, an oblong opening a, which can be opened or closed by means of a sliding door C, guided in exterior transverse ways d on the blast-pipe, said ways being preferably made of cast metal in one integral casting with a central length of the blast-pipe, in which the steam-blower B is arranged. The arrangement of the air-supply opening, and the sliding door for opening and closing the same, in the blast-pipe, near the steam-blower, is for the purpose of permitting, when the said opening a is closed, either the use of a steam-blower alone, or in conjunction with a fan-blower when an intense blast is desired, as in this case the air is propelled forward with greater force in the blast-pipe by the action of the steam-jets emitted by the steam-jet nozzles, so that, by this association, the heat in the furnace is increased and a temperature more favorable to the combustion of the iron and steel is obtained. When it is desired to use the steam-blower alone, the sliding door is opened, the fan-blower stopped, and the air drawn in directly from the atmosphere through the opening a and forced by the steam-blower to the furnace, while when the steam-supply pipe of the steam-blower is shut off and the sliding door closed the ordinary blast produced by the fan-blower can be used. In this manner the blast for steel and other furnaces can be increased by a simple and very effective means and a more effective blast obtained. An important effect obtained is that the oxidizing and scaling of the steel is prevented.

Having thus described my invention, I claim as new and desire to secure by Letters Patent—

The combination, with a steel or other furnace, of a blower, a blast-pipe connecting the blower with the furnace, said blast-pipe be-

ing provided with an opening intermediate of the blower and furnace, a steam-blower located in said blast-pipe between the opening and the furnace, and a door for opening 5 or closing said opening, substantially as set forth.

In testimony that I claim the foregoing as

my invention I have signed my name in presence of two subscribing witnesses.

H. E. PARSON.
